PAGE 2

Fig. 2

Fig. 3

FIG. 1 is a perspective view of a truck wheel balancer showing my new design.

FIG. 2 is a rear elevational view of the truck wheel balancer shown in FIG. 1.

FIG. 3 is a top plan view of the truck wheel balancer shown in FIG. 1.

The side not shown is the same as the side shown in FIG. 1.

I claim:

The ornamental design for a truck wheel balancer, substantially as shown and described.
